Patented June 22, 1976

240,322

FLEXIBLE LIGHT

David E. Staub, Clearwater, Fla., assignor to
Concept, Inc., Clearwater, Fla.

Filed Mar. 3, 1975, Ser. No. 554,752

Term of patent 14 years

Int. Cl. D26—02

U.S. Cl. D48—24 A

Fig. 1.

Fig. 2.

Fig. 3.

Fig. 4.

FIG. 1 is a front elevational view of the flexible light showing my new design;

FIG. 2 is a side elevational view of the flexible light illustrated in FIG. 1 with the opposite side being substantially a mirror image thereof;

FIG. 3 is a rear end view of the flexible light illustrated in FIG. 1; and

FIG. 4 is a front end view of the flexible light illustrated in FIG. 1.

What is claimed is:

The ornamental design for a flexible light, substantially as shown.
